Primary Examiner — Sandra L Morris(74) *Attorney, Agent, or Firm* — EIP US LLP(57) **CLAIM**

The ornamental design of a gaming robot, substantially as shown and described.

DESCRIPTION

FIG. 1 is a top perspective view of a gaming robot configured in accordance with a first embodiment of the present invention;

FIG. 2 is a bottom perspective view thereof;

FIG. 3 is a top plan view thereof;

FIG. 4 is a bottom plan view thereof;

FIG. 5 is a front view thereof;

FIG. 6 is a rear view thereof;

FIG. 7 is a right side view thereof;

FIG. 8 is a left side view thereof;

FIG. 9 is a perspective view of a gaming robot configured in accordance with a second embodiment of the present invention;

FIG. 10 is a bottom perspective view thereof;

FIG. 11 is a top plan view thereof;

FIG. 12 is a bottom plan view thereof;

FIG. 13 is a front view thereof;

FIG. 14 is a rear view thereof;

FIG. 15 is a right side view thereof; and,

FIG. 16 is a left side view thereof.

The broken lines in FIGS. 9-16 are for the purpose of illustrating portions of the article in which the design is embodied, and form no part of this embodiment of the claimed design.
